UNITED STATES PATENT OFFICE.

SAMUEL HERBERT YODER, OF READING, PENNSYLVANIA.

MAIL-BOX.

SPECIFICATION forming part of Letters Patent No. 632,390, dated September 5, 1899.

Application filed December 27, 1898. Serial No. 700,322. (No model.)

To all whom it may concern:

Be it known that I, SAMUEL HERBERT YODER, a citizen of the United States of America, and a resident of Reading, county of Berks, and State of Pennsylvania, have invented a new and useful Improvement in Mail-Boxes, of which the following is a specification.

At present it is common to provide in the various towns and cities, on the streets, in hotels, and other places, mail-boxes from which collections are made by the carrier at stated intervals which are marked upon a slip attached to some outside portion of the box in plain sight, so as to serve the public as a notice when collections are made, and hence to let them know how soon their mail will be taken to the nearest post-office station. Of course it becomes almost impossible and usually impractical for the carrier or postman to make his rounds so as to arrive at each box at the specified time, and consequently the sender does not know whether the postman has just called or is soon to arrive. If he did know this point, he would be able to get the letter to the office by going there himself in those cases where the postman may have called only a few moments before the sender arrived at the box. Again, with the present system an inspector must stop to unlock and open and close each box in order to learn whether the postman has or has not been negligent in his duties as collector.

I have provided a mail-box which overcomes the difficulties briefly alluded to above, and the same is described herein by reference to the accompanying drawings.

Figure 1 is a front elevation of the device embodying my invention as the mail-box appears in actual use except that certain figures which may be added by hand or by a stamp are not indicated on the same, the box being shown as ready for the market and as supplied to the office where it is to serve for four collections per day. Fig. 2 is a view of the same box on a greatly-enlarged scale and with the upper part broken away. The front plate, indicator-hand, fastening-screws, and one or two unessential details are omitted in order to show the interior. The dotted lines show the different phases of the door for removing the mail when unlocked by the postman. Fig. 3 is a view of one part of the

mechanism by itself in order to show better its relation to the remaining parts with greater clearness. Fig. 4 is a similar view and for similar reasons of another detail of the device.

a represents the box for containing the mail, which may be dropped into the same in the usual or other manner by passers-by. On one side thereof is a frame *b*, attached to the box *a* by means of screws *c* in holes *d*. The frame retains a glass plate *e*, behind which is a plate having the slip of paper or similar material printed with a circular scale *f*. The plate which carries the paper and graduated scale *f* is directly behind the paper, and as far as construction is concerned the said plate and paper may be considered identical, as the scale *f* could be printed or marked directly upon the said plate. The index-hand, which is adapted to point out different marks on the scale, is lettered *g* and is fastened to the arbor *h*, which is shown in Fig. 2 and passes through the hole *i*. (See Fig. 3.) To this arbor *h* is also attached securely a ratchet-wheel *j*, having in this particular box twelve teeth, some of which are shown, while the others are omitted. The number of teeth is immaterial so long as the device is so proportioned that when the door *k* is closed four times the wheel will have turned around once. Such proportioning can be carried out by any mechanic, and hence the designing may not be described at any further length. The arbor *h* being fixed to both the ratchet-wheel *j* and hand *g*, the latter rotates every time the wheel *j* rotates. The hand *g* is on one side of the scale *f* and the wheel *j* on the other side. *l* is a lever having a central hole *i*, through which loosely passes the arbor *h*, so that the said lever may turn freely on the said arbor in either direction and rest on the stop *m* in the normal position. One arm *l'* is extended and brought around and down under the arbor *h* to act as a retractile weight, the same being preferred over a spring because more reliable and durable for outside use. The extended arm referred to is lettered, as stated, *l'*. This arm must be of such weight as to cause the lever *l* to rest against the stop *m* with definite pressure. On opposite sides of the arbor *h* are holes *n* and *o* in the lever *l*. A pin *p* extends from the hole *n* and carries

loosely a pawl q , that engages with the ratchet-wheel j and has a counterweight q' , tending to retain the pawl q in engagement with the said wheel j . In the hole o is another pin r , which carries loosely a clutch t , being one end of a lever, the other end being lettered s , which is provided at its free end with a knob s' . This knob s' lies in the path of the door k , whether the latter is opening or closing. The door k is hinged at the lower right-hand corner of the box, as indicated at k' . When the door is closing, it strikes the knob s' and drives it along with the door, and the lever l with it, because the clutch t strikes the surface of the lever at l'' . When the door is being opened, on the other hand, the knob s' is driven with it for a short distance, but turns about the pin r without turning the lever farther than the stop m , because the clutch t simply moves away from the surface l'' on the lever l . The tooth u on the clutch t prevents the knob s' from going too far, as said tooth would strike against the surface l'' , as is likely to happen when the door is opened violently.

v is a pawl engaging with the wheel j and is fastened loosely to the pin v' , which projects from the same plate that holds the scale f . The counterweight s'' for the pawl keeps the same engaged with the wheel.

The details of mechanical construction having been described I will now set forth the statement of the complete operation.

The postman in making his rounds unlocks the door k and pulls it forward, removes the mail, and shuts the door again, all in the ordinary way as at present practiced in the postal service. The effect of the door upon the knob s' has already been set forth. As a consequence when the knob is moved by the shutting of the door the lever l turns, causing the pawl q to feed the ratchet-wheel j to the right to a predetermined distance. The door by this time has reached about its lowest point, and the knob has escaped contact therewith as it is pushed outside of the limit of the path of the door, which is indicated by the dotted line or arc w . Being thereby released from the door, the knob and the lever l and all attached thereto swing back through the action of the weight l' . When the lever l has swung a certain distance, it comes to rest by striking the stop m , where it is in its normal position. The pawl v holds the ratchet-wheel in its new position. The device should be so proportioned in all cases that a certain predetermined number of openings of the door will make a complete rotation of the index-hand g , and this number should, preferably, be the number of trips of the postman per day. If the postman is to make four trips or collections, he will shut the door four times, and this number of impulses on the wheel j should turn it around once.

My plan is to provide parts of mechanism of such proportions that one may be used for boxes where four collections are to be made and indicated per day, another where there

are less collections to be indicated, another where there are six, and so on indefinitely. Say there are as many as twenty different sizes. Then they may be considered as so many classes, one class being suitable for hundreds of towns, the next class for another hundred or more towns, and another class for another hundred or more towns, and so on, so that a few classes will suit a great many towns in the United States, and, similarly, suitable arrangements can be made in other countries. I have shown the construction so that others may build the device; but I have not shown all the different sizes, as size and proportion do not limit my invention. A large city would use some of several classes.

To save the cost of manufacture and multiplicity of the parts by having different sizes, as above set forth, I may avoid the same by having but one size, with such proportions as will answer for the maximum number of calls per day; but where there are less collections the trips may be indicated to four or five or six, &c., and then on the first trip in the morning the postman or inspector may reset the device to the zero-point, and thus the same box is ready for the next set of collections, and so on indefinitely. This setting could be effected by tripping the door back and forth by rapid openings and closings until the hand g is brought back to the starting-point, all this being done after the last trip of the postman on any particular day, or the arbor h could be turned manually backward.

It now becomes evident that the collections need not be made at regular intervals, although the ratchet-wheel and index-hand are moved through equal distances at each impulse. The first division on the scale may be marked "7.30 a. m.", for instance, and the next "11 a. m.", the next "12 m.", the next "4 p. m.", and so on as long as the number of indications of time on the scale equals the number of impulses of the wheel per day.

My invention has been so carried out that it is not necessary to construct new boxes for the department, but any of the present boxes may be equipped without making any change therein whatever.

I claim as my invention—

1. In a mail-box, the combination with the box, of a door hinged thereto, an index for causing a different indication at each closing of said door, a reciprocating lever for operating said index and a secondary lever lying in the path of said door and locked to the first lever in one direction of the movement thereof, and unlocked from said lever in the other direction of movement.

2. In a mail-box, the combination with the box, of a door hinged thereto a lever whose one arm lies in the path of said door, a clutch on the other arm, a second lever adapted to be gripped by said clutch, and carrying a pawl, a ratchet-wheel and index controlled by said pawl, a stop m , for limiting the movement of the second lever, a tooth u for limit-

ing the movements of the first lever and a second pawl engaging with the wheel, as and for the purpose set forth.

3. In a mail-box the combination with a door hinged thereto of an index for indicating the number of times the door is closed, a lever for operating said index and having a lug on thereon and a secondary lever pivoted to said lug and normally bearing against said

lever to be locked thereto and adapted to turn relatively to said first lever when operated by the opening of said door.

Signed this 20th day of December, 1898.
